Primary Examiner — Amber R Stiles*Assistant Examiner* — Molly K. Orzechowski(74) Attorney, Agent, or Firm — Banner & Witcoff, Ltd.(57) CLAIM

The ornamental design for a shoe as shown and described.

DESCRIPTION

FIG. 1 is a front perspective view of a shoe showing our new design;
 FIG. 2 is a side view thereof;

FIG. 3 is an opposite side front perspective view thereof; and,
 FIG. 4 is an opposite side view thereof.

The racetrack-shaped broken line within the claimed panel represents an eyelet that forms no part of the claimed design. The broken lines immediately adjacent to the bottom of the claimed panel define bounds of the claimed design and form no part thereof. The broken lines depicting the remainder of the shoe form no part of the claimed design.
